Daniel G. Slover

UNITED STATES PATENT OFFICE.

DANIEL C. STOVER, OF FREEPORT, ASSIGNOR TO I. L. ELLWOOD & CO., OF DE KALB, ILLINOIS.

MACHINE FOR TWISTING AND SPOOLING BARBED-WIRE FENCING.

SPECIFICATION forming part of Letters Patent No. 297,726, dated April 29, 1884.

Application filed March 2, 1883. (No model.)

To all whom it may concern:

Be it known that I, DANIEL C. STOVER, of Freeport, Stephenson county, State of Illinois, have invented certain new and useful Improvements in Machines for Twisting and Spooling Barbed-Wire Fencing; and I do hereby declare that the following is a full, clear, and exact description of the same, reference being had to the accompanying drawings, forming a part of this specification, and in which—

Figure 1 represents a top or plan view of my aforesaid improved twister and spooler. Fig. 2 represents a side view of said twister and spooler, looking in the direction of arrow 1, Fig. 1. Fig. 3 represents a vertical section on line *a*, Fig. 1, looking in the direction of arrow 2, same figure. Fig. 4 represents, upon an enlarged scale, a vertical section on line *b*, Fig. 1, looking in the direction of arrow 3 of said Fig. 1, showing a side view of the distributing device, hereinafter more fully described; and Fig. 5 represents, upon the same enlarged scale as Fig. 4, a side view of a part of the machine, also hereinafter more fully described, looking in the direction of arrow 4, Fig. 1.

My invention comprises certain improvements upon the twister and spooler for which Letters Patent No. 241,747 of the United States were granted to me, assignor to I. L. Ellwood & Co., May 17, 1881.

The nature of my invention consists in the combination of a spring with the spool and its driving-gear; also, in the combination, with the devices for rotating the spool, of mechanism for readily adjusting the friction required in coiling the wire upon the spool, as hereinafter more fully described.

My said present improvements may be usefully applied to other barbed-wire twisting and spooling-machines than that patented as above, and therefore I do not confine myself to their use in said patented machine.

To enable those skilled in the art to which my invention belongs to make and use the same, I will proceed to describe it more in detail.

In the drawings, A represents a frame, which turns in suitable bearings, B B', at each end, formed upon or secured to the upper ends of supporting-frames C C. The end of frame A

which fits in the bearing B' is made in the form of a hollow hub, *c*, for the twisted strand D to pass through to the spool E, while the opposite end of said frame, which turns in the bearing B, is provided with a sleeve, (shown by dotted lines *d*,) upon which the driving-pulley F is secured. Said pulley may be connected with any suitable and convenient mechanism for turning frame A and parts connected thereto, to twist the wires *e e'* together to form the strand D, as shown. The sleeve *d* fits over a horizontal shaft, *f*, upon one end of which is secured a bevel-gear, G, and upon its other end a pulley, H, which gear and pulley keep the shaft *f* in its proper position longitudinally, and also serve the purposes hereinafter described. As fast as the strand D is twisted by turning frame A and other parts, as before described, it is drawn forward and coiled upon the spool E by turning said spool, the end of the strand having been previously secured to it. The spool E is turned as aforesaid in the following manner: It is fitted loosely on an adjustable spindle, I, which may be drawn out to remove the spool, when filled, by drawing out pin *g*. The spool, when fitted in place, is held so as to turn with spur-gear J by one or more strong flat springs similar to spring *h*, which is secured to the side of said spur-gear, (see Figs. 1 and 3,) and held in position against the hub E' of the spool by means of a pin, *i*, also secured in the spur-gear J. The spur-gear J engages or gears with a spur-pinion, M, on the short shaft L, which is journaled in bearings in the bracket N and the side of frame A, and to which, at its inner end, is fixed the bevel-gear K. The gear G engages with the gear K. The gear G being prevented by a brake or friction-strap, O, on the pulley H, as hereinafter explained, from turning freely with the frame A, the gear K travels over the said gear G, and is thereby revolved on its axis, and through the shaft L, pion M, and spur-gear J turns the spool E. 95

By the foregoing construction and arrangement it will be seen that as the twisting-frame is turned by means of the driving-pulley F to intertwist the wires *e e'*, as before described, the twisted strand D is drawn forward and coiled upon the spool E at the same operation.

It is obvious that as the coil being formed

upon the spool is increased in size a greater tension upon the twisted strand is produced and a greater amount of power is necessary to turn said spool and coil. It is therefore necessary, in order to properly coil said strand, that the tension may be partially relaxed upon the same and governed independent of the twisting and coiling operation. To accomplish this result, I arrange a friction-strap, O, over the pulley H, which may be clasped tightly around said pulley to hold the bevel-gear G rigidly, or loosened so as to allow it to turn by depressing or raising the arm k of said strap or collar O, its other arm, k', being held in position against a stationary pin, l, secured in bearing B of the machine. Arm k possesses the yielding qualities of a spring. When the coil is first started upon the spool, only a slight pressure is required upon the arm k to hold 20 the bevel-gear G, and at the same time allow it to turn in case of a too strong tension being produced; but as the coil is increased in size the pressure is increased accordingly, greater power being required to hold said bevel-gear 25 G, owing to the increased leverage between the shaft or spindle of the spool and the outside of the coil. The spring or springs h greatly facilitate the operation of quickly starting the rotation of the spool after each barbing 30 operation of the machine for applying barbs to the wire when, as is usually the case, the wire is fed intermittently through said barbing-machine. The spool E is prevented from turning back farther than the spring h can be 35 safely sprung back when under strong tension by striking the stop-pin h'.

The operation in detail is as follows: When the feed of the strand or wire D ceases, the tension thereof prevents the spool from turning. 40 The power which tended to turn the gear J continues to act, and, being sufficient to overcome the resistance of the spring h, it turns the gear J independently of the spool and bends the spring h until the latter strikes the pin h'. The motion of the gear J is also arrested until the tension of the strand D is relieved by the commencement of the feed. The spring h now returns to its former position and in returning starts the spool quickly ahead, so that it winds 45 up the strand in advance of the movement of gear J.

For convenience in operating the arm k to govern the tension upon the strand D, (the machine being about eight feet in length and 50 the attendant usually at the opposite end from

said arm next to the barbing-machine, not shown,) said arm is connected by means of cord m (passed over guide-pulleys n n) with the hub P' of a ratchet-wheel, P, which is held from turning back by a pawl or dog, P², pivoted to a rigid bearing, P³, secured to bearing B'. The strand D is properly guided as it is drawn forward by passing under a sprocket-wheel, Q, (which is fitted to turn on a stud, o, arranged in bearings p p,) and over the distributor R in 55 the form of a sprocket-wheel, which not only turns, but has a lateral traverse or endwise movement, so as to distribute the strand evenly upon the spool E as it is coiled upon the same. The finger S, journaled in a bearing 70 on the side of the distributor R, travels in the groove (11 or 13, as the case may be) of the double-threaded shaft T. As the distributor revolves it is carried by the action of the groove upon the finger S to one end of the grooved 75 portion of the shaft. The cam q at that end then turns the finger S on its journal, so that the said finger, on the further rotation of the distributing-wheel or distributor R, enters the reverse groove 13 or 11. By the action of this 80 groove the distributor is carried to the opposite end of the grooved portion of the shaft, where its lateral motion is again reversed by the cam q at that end.

Having now fully described my said invention and the manner of carrying the same into effect, what I claim, and desire to secure by Letters Patent, is—

1. The combination of a holding-spring, h, with the spool E, driving spur-gear J, and revolving frame A, in which said spool and gear are supported, substantially as and for the purposes set forth. 85

2. The combination, with the pulley H, shaft f, frame A, supporting-frame C, spool E, and 90 gearing between the spool E and shaft f, of friction-strap O, provided with arms k k', holding part l, cord m, pulleys n, ratchet-wheel P, provided with hub P', and pawl P², substantially as and for the purposes set forth. 95

3. The combination of the frame A and spool E with one or more springs, h, spur-gear J, pinion M, shaft L, bevel-gear K, bevel-gear G, shaft f, and the means for holding said shaft, substantially as and for the purposes set forth. 100
